(57) **CLAIM**

The ornamental design for a fan with two operational configurations, as shown and described.

DESCRIPTION

FIG. 1 is a top, front perspective view of a fan with two operational configurations showing my new design, the fan being in its vertical operational configuration;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a left, front perspective view of the design of FIG. 1, the fan being in its horizontal operational configuration;

FIG. 9 is a front elevational view of the design of FIG. 8;

FIG. 10 is a rear elevational view of FIG. 8;

FIG. 11 is a top plan view of FIG. 8;

FIG. 12 is a bottom plan view of FIG. 8;

FIG. 13 is a right side elevational view of FIG. 8;

FIG. 14 is a left side elevational view of FIG. 8;

FIG. 15 is an exploded view of the design of FIG. 1; and,

FIG. 16 is an exploded view of the design of FIG. 8.
